John B. Mack, Jr., Freeport, N. Y., assignor to
The American Bankers Association, New York,
N. Y., an unincorporated organization

Application April 10, 1946, Serial No. 128,467

Term of patent 14 years

(Cl. D1—10)

To all whom it may concern:

Be it known that I, John B. Mack, Jr., a citizen of the United States, residing at 40 Elm Place, Freeport, county of Nassau, State of New York, have invented a new, original, and ornamental Design for an Advertising Literature Holder, of which the following is a specification, reference being had to the accompanying drawing, forming part thereof.

In the accompanying drawing, Fig. 1 is a front perspective view, tilted at a slight angle, of an advertising literature holder showing my new design; and Fig. 2 is a side perspective view, also tilted at a slight angle, of the same holder.

I claim:
The ornamental design for an advertising literature holder, as shown.

JOHN B. MACK, JR.
